Izaak Walton Bader, Brooklyn, N.Y., assignor to Spot-nails, Inc., Long Island City, N.Y., a corporation of New York

Filed July 10, 1967, Ser. No. 7,748

Term of patent 14 years

(Cl. D54—14)

FIG. 1 is an isometric perspective view of an industrial stapling machine or similar article showing my new design.

FIG. 2 is a side elevational view thereof.

FIG. 3 is a fragmentary front elevational view thereof.

FIG. 4 is a rear elevational view thereof with the broken line portion removed for ease of illustration.

FIG. 5 is a top plan view thereof.

FIG. 6 is a bottom plan view thereof.

The characteristic features of my design reside in the full line portions of the drawings. The portions of the design not shown are similar to the portions shown.

I claim:

The ornamental design for an industrial stapling machine or similar article, as shown and described.
